(57) **CLAIM**

The ornamental design for a case for electronic communications device, as shown and described.

DESCRIPTION

FIG. 1 is a front elevational view of a case for electronic communications device showing my new design;

FIG. 2 is a rear elevational view thereof;
FIG. 3 is a left side elevational view thereof;
FIG. 4 is a right side elevational view thereof;
FIG. 5 is a top plan view thereof;
FIG. 6 is a bottom plan view thereof;
FIG. 7 is a front perspective view thereof;
FIG. 8 is a rear perspective view thereof;
FIG. 9 is a front perspective view of the inner shell component of the case shown separately for clarity of disclosure;
FIG. 10 is a rear perspective view of the inner shell component of the case shown separately for clarity of disclosure;
FIG. 11 is a front perspective view of the outer frame component of the case shown separately for clarity of disclosure;
FIG. 12 is a rear perspective view of the outer frame component of the case shown separately for clarity of disclosure;
FIG. 13 is an exploded front perspective view thereof, showing the inner shell and outer frame components separated for clarity of disclosure; and,
FIG. 14 is an exploded rear perspective view thereof, showing the inner shell and outer frame components separated for clarity of disclosure.

The case for electronic communications device, in which the claimed design is embodied, consists of an inner shell and outer frame. The claim is directed to the ornamental appearance of the case for electronic communications device in its entirety and does not extend to the ornamental appearance of the individual components of the case for electronic communications device.

The broken lines throughout the drawing figures depict portions of the case that form no part of the claimed design. The broken lines and regions bounded by broken lines form no part of the claimed design.

The interior of the case shown in FIGS. 1, 7, and 13 (specifically, that region within the innermost of the solid lines around outer edge of the interior cavity and extending to the outermost of the solid lines around the interior of the round rear opening) forms no part of the claimed design.

1 Claim, 14 Drawing Sheets
